UNITED STATES PATENT OFFICE.

CHARLES H. HILL, OF SCHENECTADY, NEW YORK, ASSIGNOR TO GENERAL ELECTRIC COMPANY, A CORPORATION OF NEW YORK.

PULL-BUTTON-CONTROLLING SWITCH.

1,096,913.

Specification of Letters Patent.

Patented May 19, 1914.

Application filed May 17, 1906. Serial No. 317,305.

To all whom it may concern:

Be it known that I, CHARLES H. HILL, a citizen of the United States, residing at Schenectady, county of Schenectady, State of New York, have invented certain new and useful Improvements in Pull-Button-Controlling Switches, of which the following is a specification.

This invention relates in general to electric switches actuated by means of solenoids or similar devices and controlled from a point remote from the switch, and more particularly to controlling means for switches of the type above indicated. Many controlling devices for this purpose at present in use are in the form of switches which take up considerable room on the switchboard, have switch-blades projecting therefrom, and contacts exposed on the front of the board in such position that objects may come into engagement with the contacts by accident, thereby causing the main switch to be operated at unexpected times. It has been proposed to place the contacts in recesses, but these recesses form lodging places for small objects of various kinds and are therefore objectionable.

The objects of the present invention are to provide a controlling device which shall take up but little room on the switchboard and shall have only knobs or similar parts projecting from the board when not in use and which may be made similar in appearance to the other switches commonly found on switchboards used with this type of device.

Another object is to provide an interlock on the control device so as to prevent more than one control circuit being closed at any time; a further object is to indicate which control circuit was last closed by the operator; and another object is to improve, in general, the construction and operation of control devices of this character.

The invention will be best understood by reference to the accompanying drawings, in which—

Figure 1 is a longitudinal sectional view of the device; Fig. 2 is an end view, showing the contacts of the control circuit and other parts in elevation; Fig. 3 is a plan view, looking at the front of the switchboard; Figs. 4 and 5 are views of parts of the device; and Fig. 6 is a diagram showing the control circuits for the main switch.

A panel 1 of slate or other insulating material is provided upon which the controlling device is mounted. Holes are bored through this panel in which tubes 2 are secured. A hole 3 is made through the panel between the holes in which the tubes 2 are mounted. An escutcheon 4 is mounted upon the front of the board and covers the ends of the tubes 2 and the hole 3. A block 5, preferably of insulating material, is mounted on the back of the board and covers the other ends of the tubes 2 and the hole 3. The escutcheon and the block 5 are held in position by means of bolts 6 which extend through the panel and engage both the escutcheon and the block; and the tubes 2 are countersunk both in the escutcheon and in the block. Controllers are mounted in the tubes 2, each controller having a stem with two portions 7 and 8 of different diameters; these portions being connected by a cone surface 9. On the portion 8 of the controller stem, a collar 10 is mounted. This collar engages one end of a spring 11 surrounding the stem 8, the other end of which bears against the escutcheon 4. This spring tends to hold the controller in the position shown in Fig. 1. A knob 12 is mounted on the end of the stem 8 and forms a means by which the operator may move the controller. This knob is normally held against the escutcheon by the force exerted by the spring 11. On the other end of the controller, on the portion 7 of the stem, bridging contacts 13 and 14 are mounted. Fixed contacts 15 are secured to the block 5 in such position that when the controller is moved against the tension of the spring 11, the bridging contacts 13 and 14 may be brought into engagement with the fixed contacts 15, thereby completing a circuit from one of said fixed contacts to the other.

It is evident that with the structure above described, the only operative movement of the controller-stem is a movement away from the panel, since the knob on the end of the controller-stem is normally in engagement with the panel, thereby preventing movement of the controller-stem except by pulling upon the knob. It is apparent that any kind of a stop could be substituted for the panel. With a structure of the kind described, the normal mode of operation is to pull upon the controller knob, thereby closing the controller circuit, after which the knob is released, and the controller-stem re-

turns to normal position. Accidental operation of the controller switch, by pushing upon the knobs or by objects falling upon the switchboard and striking the knobs, is 5 avoided, and at the same time the contacts, being placed behind the panel, are thoroughly protected from accidental contact or derangement.

The block 5 is provided with a groove in 10 which is loosely mounted an interlock 16 in the form of a block, as shown in Fig. 5, having inclined ends and a hole 17 in the middle thereof. It is necessary that the length of the interlock be greater than the distance 15 between projections on the controller stems when the stems are in operative position, and therefore the length of this block is greater than the distance between the portions 7 of the controller stems. As shown 20 in Fig. 1, the length of the block is approximately the distance between the surface of the portion 7 of one controller stem and the surface of the portion 8 of the other stem. The ends of the interlock project into openings 25 in the block 5 in line with the axis of the tubes 2. The portions 7 of the controller stems slide in these openings and the openings are approximately of the same size as the portions 7 of the stem. As a result 30 of this arrangement it is impossible to bring both contacts 13 and 14 into engagement with contacts 15 at the same time. The interlock is held in position in the groove in the block 5 by means of a supporting-plate 35 18 which is held in position by the bolts 6.

A base-plate 19 is counter-sunk in the block 5 and is held in position between the block and the panel 1, by means of pins 20 which engage holes in the block 5. The 40 base-plate 19 has a hole in the middle thereof corresponding with the hole 22 in the block 5. A pivot 21 is mounted in the base-plate 19 transverse to the hole 22. The base-plate also carries pillars 23 firmly attached 45 thereto at one end and carrying at the other end, spring-blades 24, which, as shown in Fig. 4, have projections 25 pointing toward each other so that the space between the projections is considerably less than the 50 space between the remaining portions of the spring-blades. An indicator 26, preferably circular in cross-section, is mounted on the pivot 21 and has one end loosely fitting in the hole 17 of the interlock 16, while the 55 other end carries an indicator plate 27 which moves in front of a window 28 in the escutcheon 4. The indicator plate is preferably divided into two parts, one of which may be of one color and the other of another, or the indicator plate may carry words or 60 letters corresponding to the position of the indicator.

The relation in which this controlling device is used is shown in Fig. 6, in which a 65 circuit-breaker is represented diagrammati-

cally. This circuit-breaker has a contact 29, actuated by a toggle 30, which is straightened for the purpose of bringing the contact 29 into engagement with fixed contacts by operating means, preferably consisting of an actuating solenoid 31, the core of which engages the toggle 30 and straightens it when the solenoid is energized. A catch 32 in the form of a bell-crank lever engages the end of one of the links of the toggle to hold the circuit-breaker closed. A trip-coil 33 is provided, the core of which, when the coil is energized, strikes one arm of the bell-crank 32 and moves it so as to permit the circuit-breaker to open. The solenoid 31 and the coil 33 are energized from a control or supply circuit having leads 34 and 35. As shown in Fig. 6, the lead 35 of the supply circuit is connected to one end of the coil 33, the other end of said coil being connected 80 by means of a lead 36 to a contact 15 of the controlling switch. The lead 35 is also connected to one end of the winding of the solenoid 31, the other end of which is connected by means of the lead 37 to another contact 15 of the controlling device. The other lead 34 of the supply circuit is also connected to contacts on the controlling device as shown in Fig. 6.

With a controlling arrangement of the type above described, it is desirable to provide means whereby only one controller-stem at a time may be operated. It is evident that if both the opening and the closing solenoids were energized the switch would stay closed only so long as the operator held the circuit closed through the closing solenoid. To operate the switch properly under such circumstances would require care and attention on the part of the operator, as 10 it would be necessary to open the circuit of the trip-coil before opening the circuit of the closing coil. Such a tax on the attention of the operator is undesirable, especially where this device controls switches used in 11 synchronizing. Under such circumstances, the operator must watch the synchronizer, and the controlling switch for closing the main switch should be of the type requiring a minimum of attention and care on the part 12 of the operator. When the switches are provided with an interlock, as above described, there is no possibility of energizing both solenoids at the same time, so that all that the operator has to do is to pull one controller 12 knob and then release it.

The operation of the device is as follows: If it be assumed that the circuit-breaker is closed and the operator desires to open it, the bridging contact 13 is brought into engagement with the contacts 15, closing a circuit through the lead 34, lead 36, and trip-coil 33. As a result, the trip-coil 33 is energized, the core rises, and striking the catch 32 releases the toggle 30 and permits the cir- 13

cuit-breaker to open under the action of a spring or gravity. The operator then releases the knob 12, thereby permitting the controller to assume its normal position with the bridging contact 13 out of engagement with the contact 15. When the operator moves the controller, however, for the purpose of bringing the bridging contact 13 into engagement with the fixed contacts 15, the cone surface 9 engages the beveled end of the interlock 16 and moves the interlock to one side; but the return of the controller to its normal position does not affect the interlock, which remains in the position to which it was moved in the first place. As a result, the parts are left in the position shown diagrammatically in Fig. 6. The circuit-breaker is open and the interlock has been moved, thereby moving the indicator to a position which shows the attendant that the last movement of the controlling device was for the purpose of opening the circuit-breaker. The indicator tends to assume one extreme position or the other since the projections 25 on the spring-blades 24 are so placed that they tend to throw the indicator from the middle position. It is therefore impossible to leave the indicator and the interlock in a neutral position. If now the attendant desires to close the circuit-breaker, the bridging contact 14 is brought into engagement with the fixed contacts 15, this movement shifting the interlock and thereby the indicator to a position which shows that the last movement of the controlling device was for the purpose of closing the circuit-breaker. When the bridging contact 14 is in engagement with the fixed contacts 15, the circuit is completed from the lead 34, through the bridging contact 14, lead 37 and winding of the solenoid 31. As a result, the solenoid is energized and the core is moved to straighten out the toggle 30, thereby closing the circuit-breaker which is locked in the closed position by means of the catch 32. The controller is released and the bridging contact 14 moves out of engagement with the fixed contacts 15, but the interlock and the indicator remain in position to which they were last moved, showing the attendant that the circuit-breaker is closed.

Obviously, many changes may be made in the form of my invention, and I therefore do not wish to be limited to the exact form shown, but intend to cover by the terms of the annexed claims all changes and modifications within the spirit and scope of my invention.

60 What I claim as new, and desire to secure by Letters Patent of the United States, is,—

1. In a circuit-controlling device, the combination with a plurality of switches, of in-

terlocking means for said switches, a pivoted lever having one end engaging said interlock 65 and the other end carrying an indicator, and yielding means engaging said lever to move it from intermediate position.

2. The combination with a support and a plurality of switches mounted upon said support biased to normal inoperative position, operating handles for said switches, means for moving said switches into operative position when said handles are pulled away from said support toward the operator, 70 of an indicator constructed to remain in the position in which it is set, and means whereby said indicator is set in response to the movement of any of said switches out of normal position by movement of its operating 75 handle away from said support and is left unaffected by the return of said switch to normal position.

3. The combination with a support and two switches mounted on said support, each 85 switch having contacts behind said support, operating knobs in front, and means for resiliently holding said switches open with said knobs immovable toward said support, of an indicator for said switches, and actuating means whereby said indicator is actuated in response to the closing of either of said switches by movement of its operating 90 knob away from said support and is unaffected by return of said switches to open 95 position.

4. The combination with a support and two switches secured to said support side by side, each switch comprising an operating knob in front of said support, a stem extending through said support, contacts behind said support, and a spring for holding said knob against said support when the switch is in normal position, of an indicator constructed to remain in the position in 100 which it is set, and projections on said stems for setting said indicator in response to movement of either of said switches out of normal position and leaving said indicator set until the other switch is moved out 105 of normal position.

5. The combination with two switches biased to normal position, of a movable interlock between said switches, actuating means controlled by said switches to move 115 said interlock in response to movement of either switch out of normal position and to leave said interlock unaffected by the return of said switch to normal position, and an indicator actuated by said interlock. 120

In witness whereof, I have hereunto set my hand this 16th day of May, 1906.

CHARLES H. HILL.
